UNITED STATES PATENT OFFICE.

WILLIAM H. WOODARD, OF SIOUX CITY, IOWA, ASSIGNOR OF ONE-HALF
TO FRED J. HANSEN, OF SAME PLACE.

WEATHER-STRIP.

SPECIFICATION forming part of Letters Patent No. 390,637, dated October 2, 1888.

Application filed May 7, 1888. Serial No. 213,018. (No model.)

To all whom it may concern:

Be it known that I, WILLIAM H. WOODARD, a citizen of the United States, residing at Sioux City, in the county of Woodbury and 5 State of Iowa, have invented certain new and useful Improvements in Weather-Strips; and I do hereby declare the following to be a full, clear, and exact description of the invention, such as will enable others skilled in the art to 10 which it appertains to make and use the same.

This invention relates to that class of weather-strips which are used to close the joints between window-sashes and the frames in which they are fitted to slide against the entrance of 15 cold air, dust, &c.; and its object is to permit the sash to be fitted so loosely in its frame that it will slide therein with perfect freedom, even when it becomes swelled in wet weather, and yet to prevent the passage of air and dust, and 20 to hold the sash raised without offering any material resistance to the act of raising it.

To this end my invention consists in the construction and combination of parts forming the weather-strip and dust-guard, hereinafter described and claimed, reference being had to the accompanying drawings, in which—

Figure I is a front elevation of a window-sash and a portion of the jamb, showing my invention. Fig. II is a transverse section of one 30 rail of the sash and a portion of the adjacent jamb, showing my invention; and Fig. III shows a modification of the same.

Number 5 represents the sash, 6 the side jambs, and 7 the sill of the frame, in which the 35 sash is here shown as fitted to slide vertically.

8 is an elastic cord or packing, and 9 an M-shaped sheet-metal bead, preferably of zinc.

In the two side edges of the sash I cut grooves, each shaped to receive both the packing 8 and 40 the bead 9. The bead may be secured to the jamb in any usual way, such as by entering thin grooves, as shown in Fig. II, or by being lightly nailed at its ends, as in Fig. I. In each case I prefer to support the bead wholly upon 45 its edges, leaving its middle portion, 10, free to spring out and in. The cord or packing 8 should be somewhat elastic, so that it will yield to pressure and conform to the grooves in the sash and the bead so closely as to exclude 50 both air and dust when half buried in the bead and half in the sash, as shown in Fig.

II. In service this packing, properly proportioned to its surroundings, will offer sufficient friction by its whole length bearing on the bead to hold the sash suspended at any point to which it may be raised, and yet the anti-frictional 55 nature of the zinc bead permits the sash to be started with very little effort to move up or down. Any considerable pressure in the center of the groove in the bead springs it backward at that point and tips the sides inward, thus pinching upon the packing all around its 60 projecting portion with about equal pressure.

I account for the ease with which the sash may be moved either way against an amount 65 of friction which securely holds it when at rest on the principle of a series of braces or pawls attached to the sash with their ends to drag against the bead, these braces being represented in the elastic character of the packing. 70 When the sash is moved either way, the friction of the packing on the bead drags the particles of the packing backward, and thereby compresses them toward the sash, leaving the sash to move with freedom. Then when the 75 sash is stopped the particles, being released from the rubbing action, spring outward and hold the sash. The elasticity of the packing and of the rib have a joint action in counter-acting the effect of the sash being swelled in 80 wet weather. The sash is so loosely fitted in the frame that its swelling never causes it to fill the frame and become tight. In fact, the usual wooden bead between sashes and the strips at the front and rear faces of the sash 85 generally used to form the groove for the sash to slide in may be dispensed with if the bead is securely fastened so as to form a guideway for the sash. Part of the advantages of my invention may be obtained by using my elastic 90 sheet-metal bead 9 in combination with a sash grooved to receive it and a central rib of the sash left projecting to enter the groove in the bead, as shown at 12, Fig. III. In that case the width of the rib 12 at its base should be a 95 little less than the corresponding width of the groove in the bead, in order that the sides of the bead may spring inward to compensate for pressure in the bottom of the groove when the sash swells. The cord or packing may serve 100 in the same manner to the extent required, in combination with the bead at the top and bot-

tom joints of the sashes, to close the joints; but as the bead projecting above the window-sill would sometimes be objectionable the cord may there have only a shallow groove in the 5 sash and project enough below to serve as a packing for the joint. The cord in Fig. II provides the sash with a rib corresponding to the rib 12 in Fig. III.

The cord or packing used without the bead 10 9, I do not suppose to be new, and I do not claim it.

Having thus fully described my invention, what I desire to secure by Letters Patent is the following:

- 15 1. The combination of the **M**-shaped sheet-metal bead 9, a window-frame supporting the bead, and a sash fitted to slide loosely in the frame and grooved in its edge to receive the bead and provided with a rib in this groove to 2c fit the groove in the said bead, substantially as shown and described.

2. The combination of a window-frame, an **M**-shaped sheet-metal bead resting its edges on the frame and free to spring midway, and a sash grooved to receive the bead, and provided 25 with a rib in its groove to bear in said midway portion of the bead, substantially as shown and described.

3. The combination of a window-frame, an **M**-shaped sheet-metal bead secured to the 30 frame with its edges resting thereon and its midway portion free to spring, an elastic packing-cord adapted to be half buried in the groove in the said bead, and a sash grooved to receive the said bead and the other half of the cord, 35 substantially as shown and described.

In testimony whereof I affix my signature in presence of two witnesses.

WILLIAM H. WOODARD.
